UNITED STATES PATENT OFFICE.

IRVING J. KAUDER, OF BROOKLYN, NEW YORK.

DESIGN FOR A VAMP OF A SHOE.

59,658.

Specification for Design.

Patented Nov. 15, 1921.

Application filed July 23, 1921. Serial No. 487,190. Term of patent 3½ years.

To all whom it may concern:

Be it known that I, IRVING J. KAUDER, a citizen of the United States, and a resident of the borough of Brooklyn, in the city and State of New York, have invented a new, original, and ornamental Design for Vamps of Shoes, of which the following is a specification, reference being had to the accompanying drawings, forming part hereof.

In the said drawings, Figure 1 is a side view of a shoe, embodying the new design for a vamp, and Fig. 2 is a top plan view of the shoe embodying my new design.

I claim:

The ornamental design for a vamp of a shoe, as shown.

In witness whereof I have hereunto signed my name at the city of New York, State of New York, this 19th day of July, 1921.

IRVING J. KAUDER.
